UNITED STATES PATENT OFFICE.

JUSTUS A. TRAUT, OF NEW BRITAIN, CONNECTICUT, ASSIGNOR OF ONE-HALF TO HENRY C. HIND, OF SAME PLACE.

BOX-HANDLE.

SPECIFICATION forming part of Letters Patent No. 391,283, dated October 16, 1888.

Application filed August 13, 1888. Serial No. 282,541. (No model.)

To all whom it may concern:

Be it known that I, JUSTUS A. TRAUT, a citizen of the United States, residing at New Britain, in the county of Hartford and State 5 Connecticut, have invented certain new and useful Improvements in Box-Handles, of which the following is a specification.

My invention relates to improvements in handles for packing boxes of paper or other 10 boxes of thin material; and the object of my invention is to make a cheap and convenient handle which can readily be attached to ordinary boxes, and which also may be detached for application to another box when desired.

15 In the accompanying drawings, Figure 1 is a perspective view of one end of a packing-box and its cover with one of my box-handles applied to the box. Fig. 2 is a perspective view of the handle alone. Fig. 3 is a perspective 20 view of one end of a box and cover with my handle applied to the box. Fig. 4 is a like view of the same with my handle applied to the box-cover, and Fig. 5 is a front elevation of my box-handle.

25 I prefer to construct my handle of wire bent into the form shown. It consists of a handle, 6, adapted to project horizontally, from which handle I extend obliquely upward and outward two diverging arms, 7, 7, and from the 30 outer ends of these arms I bend downwardly the return arms 8, 8, all as shown. For convenience of attachment I prefer to bend the outer end of the arms 8, 8 slightly in a direction away from the handle, as shown at 8', 8'.

35 In Fig. 1 the box A has a cover, B, which extends downwardly upon the box only a short distance. When the cover is removed, I slip the handle upon the upper edge of the box with the two arms 8, 8 upon the inside, and the arms 40 7, 7 and handle 6 upon the outside, and force them downwardly until the upper edge of the box comes in contact with the inside of the bend at the junction of the arms 7 and 8. The portions of the arms which are hidden from view and the upper edge of the box are indicated by broken lines. The lower ends of the arms 7 and 8 are also formed nearly enough in one plane, so that when the handle is applied in the manner described the spring of the ma-

50 terial acts to press or clamp the arms against the opposite sides of the paper or other material of which the box end is formed, thereby securing the handle in position against accidental displacement.

55 In stores and many other places where boxes are placed one upon another in piles side by side it is very inconvenient to withdraw any particular box, and my handle is specially adapted to be applied to such boxes, so that the box may be readily withdrawn from its 60 place, and even the entire box and its contents may be carried from place to place by taking hold of the box-handle and placing a finger under the bottom of the box at the handle end.

65 In Figs. 3 and 4 I have shown a box whose cover is substantially the height of the box, the same being what is sometimes termed a double box. For such a box I make the arms 7, 7 somewhat longer, so that the handle may come at or near the top or bottom of the box. 70 With such a box my handle may be applied either to the box or cover, as shown, respectively, in Figs. 3 and 4.

75 These handles may be made in different sizes and of heavy or light material to adapt them for use upon different styles of boxes or for boxes having light or heavy contents. When the box is worn out or its contents are exhausted, the handle can be readily detached and applied to another box for further use. 80

I am aware that a prior patent shows a removable handle for tea-cups and similar round vessels formed of wire doubled upon itself and extending upwardly to the top edge of the cup with the two members lying closely together 85 and then downwardly on the inside thereof, and the same is hereby disclaimed.

I claim as my invention—

90 The herein-described box-handle, consisting of the horizontally-projecting handle 6, the arms 7, 7, extending upwardly and diverging outwardly therefrom, and the return-arms 8, 8 at the outer ends of the arms 7, 7, substantially as described, and for the purpose specified.

JUSTUS A. TRAUT.
